HAT BLOCKING MACHINE

Joseph Sarnelle, New York, N. Y.

Application January 10, 1950, Serial No. 137,691

18 Claims. (Cl. 223—12)

1

This invention relates to hat blocking machines.

An object of this invention is to provide a highly improved machine of the character described having means for blocking brims of hats having a welted edge or a thickened edge known to the trade as a Cavanaugh edge, without damaging said edge.

Another object of this invention is to provide a machine of the character described comprising a stand, a top steam jacket mounted on the stand for sliding movement up and down, a foot pedal for depressing the top steam jacket, said stand being provided with a pair of horizontal rails, a bottom steam jacket slidably mounted on the rails from a position beneath the top steam jacket to a position offset from said top steam jacket, a steam pot attached to the underside of the bottom steam jacket, means to feed steam to the two steam jackets and to the steam pot, said top and bottom steam jackets being formed with central through openings, a member mounted on the upper side of the bottom steam jacket and having a top wall formed with a central opening to receive the brim of the hat thereon, with the crown of the hat projecting downwardly from the opening in said top wall, and projecting through the opening in said bottom steam jacket and into the steam pot, said member having a skirted wall extending downwardly from the top wall thereof, and formed with an outwardly extending bottom flange contacting the top of said bottom steam jacket, and said top wall of said member being formed at its outer periphery with an annular groove to receive the thickened edge of the brim of the hat, a ring surrounding said skirted wall of said member and adapted to rest on said flange when depressed, spring means to raise said ring above said flange and a plate attached to the underside of said top steam jacket and adapted to move downwardly upon depressing said top steam jacket for depressing said ring and pressing the brim of the hat against said top wall.

Another object of this invention is to provide in a machine of the character described a counterbalanced lever hinged to the stand, said lever being formed with a handle for depressing the lever and means on the lever for pressing a hat block within the crown of the hat downwardly.

Still another object of this invention is to provide a machine of the character described so arranged that when the lever is released it will swing upwardly by means of a counterweight and the top steam jacket will be raised by springs

5 whereby to permit the steam pot together with the bottom steam jacket and said member and ring to be slidably moved on the rails forwardly of the stand on the rails whereby the hat therein may be removed and another hat replaced for another blocking operation.

10 Still another object of this invention is to provide a strong, durable device of the character described which shall be easy to manipulate, relatively inexpensive to manufacture and which shall yet be practical and efficient to a high degree in use.

15 Other objects of this invention will in part be obvious and in part hereinafter pointed out.

19 The invention accordingly consists in the features of construction, combinations of elements, and arrangement of parts, which will be exemplified in the construction hereinafter described, and of which the scope of invention will be indicated in the following claims.

20 In the accompanying drawings in which is shown various illustrative embodiments of this invention,

25 Fig. 1 is a side elevational view of a machine embodying the invention and showing the bottom steam jacket, steam pot, presser member and ring pulled forwardly of the machine in position for replacing a blocked hat with another hat to be blocked;

30 Fig. 2 is a front view of the machine taken on line 2—2 of Fig. 1;

35 Fig. 3 is a top plan view of the machine shown in Fig. 1;

40 Fig. 4 is a cross-sectional view taken on line 4—4 of Fig. 1;

45 Fig. 5 is a cross-sectional view taken on line 5—5 of Fig. 1;

50 Fig. 6 is a view similar to Fig. 5 and showing the top steam jacket and the plate attached to its underside depressed against the brim of the hat in blocking position and showing the block within the crown of the hat depressed by the lever;

Fig. 7 is a partial view similar to Fig. 6 and illustrating a modified construction;

Fig. 8 is a perspective view illustrating the steam connection for the steam jackets and steam pot;

Fig. 9 is a top plan view of the presser member; and

Fig. 10 is a top plan view of the top presser member.

Referring now in detail to the drawing, 10 designates a hat blocking machine embodying the invention. The same comprises a stand 11. Said

stand 11 comprises a pair of similar symmetrically disposed side members 12. Each comprises a front leg 13 and a rear leg 14 of angular cross-section. The front and rear legs are interconnected by lower T-shaped braces 15 and upper angle shaped braces 16 and top angle shaped braces 17. The top braces 17 each has a top wall 18 extending inwardly and a flange 19 extending downwardly from the top wall. The flanges 19 are each formed with outwardly extending vertical lugs 20 each formed with a through opening 21. Extending forwardly from the top wall 18 to each of the side members 12 is a vertical wall 22 from which extends inwardly a horizontal flange 23 having a horizontal upper surface 24. Extending rearwardly from the rear leg portions 14 are apertured ears 25 located at the level of the braces 15. The side members 12 are interconnected by a front brace 26 attached to the front legs 13 and disposed above the braces 15 and below the braces 16. The upper ends of the rear legs 14 are interconnected by a cross brace member 30 having forwardly offset legs 31 bolted to the stand and interconnected by a web 32 spaced rearwardly of the stand. Extending upwardly from the center of the web 32 is a vertical arm 33 for the purpose hereinafter appearing.

Attached to the center of the front braces 26 and extending downwardly therefrom is an upper end 34 of a ratchet member 35. Said ratchet member 35 has a front arcuate portion 36 formed with ratchet teeth 37. Said member is furthermore formed with a central longitudinal slot 38.

Mounted on and between the apertured ears 25 is a horizontal transverse shaft 40. Pivoted to the middle of the shaft 40 is a rear end 41 of a forwardly extending lever 42 which passes through the slot 38. The lever extends forwardly of the machine and is formed with a foot pedal 43 at its forward end. Pivoted to the lever 42 as at 44 is a pawl member 45. The pawl member 45 has a pawl 46 curved upwardly and inwardly and adapted to engage the teeth 37 of the ratchet member 35. The teeth 37 are so arranged that the foot lever 42 may be depressed upon pressing down with the foot on the pedal 43. Extending from the pawl 46 forwardly and alongside the lever is an arm 48 formed with a foot pedal 49 normally slightly above the lever of the foot pedal 43. Interconnecting the pawl 46 with the lug 50 on the lever is a coil compression spring 51 which passes through the slot 38 and normally presses the pawl 46 against the ratchet member 35. When it is desired to lower the lever the foot pedal 43 need merely be pressed downwardly and the pawl 46 will ride over the teeth 37, when pressure is relieved from the foot pedal 43 the lever 42 will remain in any position to which it is depressed, as the spring 51 will pull the pawl 46 into engagement with one of the teeth 37. The pawl 46 may be disengaged from the teeth 37 by depressing the pedal 49 to permit the lever 42 to be raised in the manner hereinafter appearing.

The lever 42 is formed at a point between the front and rear legs 13 and 14 with a through opening 52. Extending from the opening 52 is a pin 53 projecting to opposite sides of the lever. Engaging the projecting portions of said pin are the lower ends of a pair of parallel links 54. Said links 54 are formed with openings at their lower ends engaging the pin 53. They are also formed at their upper ends with aligned openings 55 through which extends a cross pin 56. Engaging the portion of the cross pin 56 between the

links 54 is a counter-member 57 which extends upwardly and has a screw threaded portion 58 at its upper end receiving a nut 59 screwed thereto for the purpose hereinafter appearing.

Extending through the through openings 21 in the lugs 20 are vertical connecting rods 60. There are four connecting rods 60 as will be seen from the drawing. The lower ends of the connecting rods 60 are attached to the four corners 10 of a cross-head 61. The cross-head 61 may have inwardly curved front and rear portions 62 and 63 respectively and inwardly curved side portions 64. It is also formed with a central web 65 interconnecting the front and rear portions 62 and 63. The cross web 65 as well as the front and rear side portions are ribbed for strength. At the center of the cross-head 65 is a boss 66 formed with a central through opening through which the connecting rod 57 passes. The nut 59 contacts the top of the boss 66. Surrounding the portions of the connecting rod 60 which pass upwardly above the lugs 20 are coil compression springs 67. Supported on the upper ends of the springs 67 and guided by the rods 60 is a top steam jacket 70. The top steam jacket 70 has a top wall 71, a bottom wall 72, an inner oval wall 73, outer side walls 74, and outer end walls 74a forming steam chamber 75. Between the walls 71, 72, 73, 74 and 74a, extending outwardly from the side walls 74 are lugs 76 formed with vertical through openings 77 through which the vertical connecting rod 60 passes. The lugs 76 rest on the upper ends of the springs 67. Surrounding the portions of the vertical connecting rod 60 above the lugs 76 are coil compression springs 78. The upper ends of the rods 60 are screw threaded as at 79 and screwed thereto are wing nuts 80. The top steam chamber 70 thus floats.

It will now be understood that when the foot is pressed upon pedal 49 the pawl 46 is first released and continued downwardly pressure on the foot pedal 43 will cause the rods 60 to be lowered through the lever 42, links 54, connecting rod 57 and the connecting rods 60. Downwardly pressure on the connecting rods 60 will press the wing nuts 80 downwardly to press springs 78 which in turn will press downwardly on the ears 76 for depressing the top steam chamber 70. When the foot is slipped off the pedal 49, the pawl 46 will be engaged with one of the teeth 37 to retain the top steam jacket in depressed condition. In order to raise the top steam jacket the foot pedal 49 is depressed and the lever 42 is allowed to be raised by the springs 67.

The rear walls 74a of the top steam jacket 70 is formed with a pair of screw threaded openings 70a in which are secured a pair of pipe plugs 70b and 70c for the purpose hereinafter appearing.

Fixed to the top surface 24 and inwardly extending flanges 23 in any suitable manner are a pair of parallel horizontal guide rails 81 which extend forwardly of the machine. Slidably mounted on said side rails 81 is a bottom steam jacket 82. Said bottom steam jacket 82 has a top wall 83 and bottom wall 84, an inner oval wall 85, outer side walls 86, a front wall 87 and a rear wall 88. Between the walls 83, 84, 85, 86, 87 and 88 is a steam chamber 89. The rear wall 88 of the steam chamber is formed with screw threaded openings 90 into which are screwed pipe plugs 91 and 92 for the purpose hereinafter appearing.

Extending downwardly from the side walls 86 are guide members 93 engaging the tops and outer sides of the rails 81. The bottom steam

jacket 82 may be moved from a position directly beneath the top steam jacket to a position forwardly of the machine and entirely clear of the stand 11. Attached to the underside of the steam jacket 82 is a steam pot 94. The steam pot 94 has a bottom wall 95, an annular upstanding wall 96 and a top flange 97. Any suitable means may be provided for attaching the flange 97 to the underside of the bottom wall 84 of said bottom steam jacket 82, as by screws, bolts, or in any other suitable manner. The top of the steam pot 94 communicates with the central opening in the bottom steam jacket 82, and conforms to said opening. The bottom wall 95 is formed with a drain opening 100 and with inlet opening 101.

Attached to the top of the bottom steam jacket 82 is a hat brim presser member 104. The member 104 has a top wall 105 formed with a central oval opening 106 to receive the crown of a hat mounted thereon with the crown projecting downwardly. Extending downwardly from the outer end of the top wall 105 is a skirted wall 107 of oval shape and extending outwardly from the skirted wall 107 is a flange 108 resting on the top wall 83 of the jacket and screwed or otherwise attached thereto in any suitable manner. The member 104 may be made of aluminum if desired.

At the outer periphery of the top surface of the top wall 105 is an annular groove 110. It will now be understood that a hat H may be mounted on the presser member 104 with the brim B of the hat resting on the top surface of the top wall 105 and with the crown C of the hat projecting downwardly through the opening 106, through the central opening in the bottom steam jacket 82 and into the upper end of the steam pot 94. The hat H may be of the type which has a Cavanaugh edge. The Cavanaugh edge is a thickened edge at the upper periphery of the brim. This edge which is designated in the drawing by the letter E fits within the groove 110. The flange 108 may be formed in its upper surface with a plurality of screw threaded openings 111 for the purpose hereinafter appearing.

Slidably mounted on the skirted portion 107 of member 104 is an oval shaped ring 112 formed in its upper surface with a plurality of countersunk openings 113 coaxial with the threaded openings 111. The ring 112 is formed in its end edge with a plurality of countersunk openings 114 registering or coaxial with the countersunk openings 113. The ring 112 is furthermore formed with reduced through openings 115 interconnecting the countersunk openings 114 and 113 and coaxial therewith. Screwed to the threaded openings 111 are the lower ends of bolts 116 which pass through the openings 115. At the upper end of each bolt 116 in a socketed head 117 of the Allen bolt type. The head 117 is disposed within the countersunk opening 113. Surrounding the shank of the bolt and between the flange 108 and the underside of the countersunk opening 114 is a coil compression spring 118.

It will now be understood that the upper ends of the springs 118 project into the sockets 114 and serve to raise the ring 112 above the upper surface of the top wall 105 of member 104. However the ring 112 may be depressed thereby pressing springs 118. As the ring 112 is depressed the heads 117 of the bolts 116 move through the countersunk openings 113.

Attached to the underside of the top steam jacket 70 as by means of screws 120 is a top presser plate 121 which has a central oval opening 122. When the foot pedal is depressed to

lower the top steam jacket the plate 121 depresses the ring 112 until it contacts the top of the brim of the hat in the position in which it is mounted on the machine. When the brim is thus depressed the edge E being disposed within the groove 110 will not be crushed or damaged in any way. Due to the pressure and the heat in the steam jackets the brim of the hat will be blocked.

10 The crown block 123 made of wood or any other suitable material may be inserted into the crown C of the hat H.

15 Means is provided for pressing the block down into the crown of the hat. To this end there is attached to the arm 33 a bar 124 having an upwardly and inwardly inclined portion 125. Pivoted to the upper end of said portion 125 as at 126 is the rear end of a lever 127. Said lever 127 is formed with upwardly and rearwardly inclined arm or flange 128 on which is mounted a counter-weight 129 for normally raising the lever.

20 The lever 127 has a forwardly extending handle 130. Pivoted to the lever 127 as at 131 is a member 132 having a bottom plate 133 smaller than the opening in the plate 121. Extending upwardly from the plate 133 are a pair of bosses 134 to which are screwed screws 135 which may be adjusted to contact the lever 127. When the lever 127 is depressed the plate 133 will contact the top surface of the block 123 and press the block into the crown of the hat. A spring clip 140 may be attached to the top wall of the lower steam jacket 82 for receiving an arrowhead shaped downwardly projecting tongue 141 attached to the lever for retaining the lever in downwardly depressed position. When the lever is raised the plate 133 will be raised therewith. It will be noted that the plate 133 moves through the central opening in the upper steam jacket.

25 30 35 40 45 50 55 60 65 70 75 80 85 90 95 Means is provided for supplying steam to the upper steam jacket 70, lower steam jacket 82 and steam pot 94 and for draining the steam therefrom. To this end there is provided a steam inlet pipe 150 which may pass from the stand. The steam pipe 150 is horizontal and extends forwardly as shown in Fig. 8 of the drawing. Attached to the front end of the steam pipe 150 is an elbow 151 contacted by a valve 152 which may be controlled by a handle 154. Connected to the valve 152 is a pipe 153. The pipes 150, 153 may be metal. Attached to the rear end of the pipe 153 by a suitable coupling 154 is a flexible conduit 155 connected in any suitable manner to the inlet opening 101 of the steam pot. The outlet opening 100 of the steam pot is connected by an elbow 156 to the T-shaped fitting 157. The T-shaped fitting is connected by conduit 158 to a drain. Connected to the inlet pipe 150 is a T-shaped fitting 160, one branch of which is connected to a flexible conduit 161 connected in any suitable manner to the pipe block 70c, thus admitting live steam to the upper steam jacket 70. The pipe block 70b on the steam jacket 70 is connected by a flexible conduit 162 to the inlet 92 of the steam jacket 82. The outlet 91 of the steam jacket is connected by a pipe 163 to the T-shaped fitting 157 thus draining steam from the lower steam jacket. Attached to the front wall 87 of the lower steam jacket 82 is a handle 87a to permit the operator to move the lower steam jacket and steam pot and members 104 and 112 on the rails from the full line position of Fig. 1 to the dotted line position thereof, and back to the full line position thereof.

In Fig. 7 there is illustrated the use of the machine herein for pressing hats having brims with

welted outer edges instead of with a thickened edge as shown in Fig. 6. When pressing a hat with a welted edge with the welt either turned over the brim or under the brim it is merely necessary to place above the top wall 105 a flat plate 170 formed with a central opening 171 which registers with the opening 106 in the top wall 105. The plate 170 has an outer edge 172 which registers with the outer surface of the skirted wall 107. Thus the outer periphery of plate 170 covers the groove 110 in the top wall 105. In Fig. 7 there is shown a hat H' which has a crown C' and a brim B'. The brim B' has a welted outer edge W which rests on the plate 170. When the upper steam jacket is depressed the plate 121 presses down on the brim of the hat and the welted edge is pressed against the plate 170. The same operation can be accomplished should the welted edge W be turned in against the underside of the brim B'.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A hat blocking machine comprising a stand, rails attached to the stand, and extending therefrom, a spring supported upper steam jacket slidably mounted on the stand for up and down movement, a lower steam jacket slidably mounted on said rails and slideable from a position in front of the stand to a position over the stand and below the upper steam jacket, a steam pot fixed to the underside of the lower steam jacket, said lower steam jacket being formed with a central through opening communicating with the interior of the steam pot, a hat brim pressing member on the top of the lower steam jacket, said pressing member being provided with a top wall formed with a central opening so that the brim of the hat may be placed on said top wall with the crown of the hat projecting downwardly through the central opening in said top wall and through the central opening of the lower steam jacket and into the upper end of the steam pot, said presser member being further formed with a skirted wall extending downwardly from the outer end of said top wall and with an outwardly extending flange at the lower end of said skirted wall and a ring slidably mounted and surrounding said skirted wall, spring means interposed between the ring and said flange for resiliently urging the ring upwardly, and a plate fixed to the underside of the top jacket and means for lowering the top steam jacket for pressing the ring downwardly toward the flange whereby said plate will press against the upper surface of the brim on said top wall.

2. A hat blocking machine comprising a stand, rails attached to the stand, and extending therefrom, a spring supported upper steam jacket slidably mounted on the stand for up and down movement, a lower steam jacket slidably mounted on said rails and slideable from a position in front of the stand to a position over the stand and below the upper steam jacket, a steam pot fixed to the underside of the lower steam jacket, said

lower steam jacket being formed with a central through opening communicating with the interior of the steam pot, a hat brim pressing member on the top of the lower steam jacket, said pressing member being provided with a top wall formed with a central opening so that the brim of the hat may be placed on said top wall with the crown of the hat projecting downwardly through the central opening in said top wall and through the central opening of the lower steam jacket and into the upper end of the steam pot, said presser member being further formed with a skirted wall extending downwardly from the outer end of said top wall and with an outwardly extending flange at the lower end of said skirted wall and a ring slidably mounted and surrounding said skirted wall, spring means interposed between the ring and said flange for resiliently urging the ring upwardly, and a plate fixed to the underside of the top jacket and means for lowering the top steam jacket for pressing the ring downwardly toward the flange whereby said plate will press against the upper surface of the brim on said top wall, and means for limiting upward movement of said ring relative to said flange.

3. A hat blocking machine comprising a stand, rails attached to the stand, and extending therefrom, a spring supported upper steam jacket slidably mounted on the stand for up and down movement, a lower steam jacket slidably mounted on said rails and slideable from a position in front of the stand to a position over the stand and below the upper steam jacket, a steam pot fixed to the underside of the lower steam jacket, said lower steam jacket being formed with a central through opening communicating with the interior of the steam pot, a hat brim pressing member on the top of the lower steam jacket, said pressing member being provided with a top wall formed with a central opening so that the brim of the hat may be placed on said top wall with the crown of the hat projecting downwardly through the central opening in said top wall and through the central opening of the lower steam jacket and into the upper end of the steam pot, said presser member being further formed with a skirted wall extending downwardly from the outer end of said top wall and with an outwardly extending flange at the lower end of said skirted wall and a ring slidably mounted and surrounding said skirted wall, spring means interposed between the ring and said flange for resiliently urging the ring upwardly, and a plate fixed to the underside of the top jacket and means for lowering the top steam jacket for pressing the ring downwardly toward the flange whereby said plate will press against the upper surface of the brim on said top wall, and means for limiting upward movement of said ring relative to said flange, a lever pivoted to said stand and means to press the hat block placed within the crown of the hat on said pressing member downwardly against said crown.

4. A hat blocking machine comprising a stand, rails attached to the stand, and extending therefrom, a spring supported upper steam jacket slidably mounted on the stand for up and down movement, a lower steam jacket slidably mounted on said rails and slideable from a position in front of the stand to a position over the stand and below the upper steam jacket, a steam pot fixed to the underside of the lower steam jacket, said lower steam jacket being formed with a central through opening communicating with the in-

terior of the steam pot, a hat brim pressing member on the top of the lower steam jacket, said pressing member being provided with a top wall formed with a central opening so that the brim of the hat may be placed on said top wall with the crown of the hat projecting downwardly through the central opening in said top wall and through the central opening of the lower steam jacket and into the upper end of the steam pot, said presser member being further formed with a skirted wall extending downwardly from the outer end of said top wall and with an outwardly extending flange at the lower end of said skirted wall and a ring slidably mounted and surrounding said skirted wall, spring means interposed between the ring and said flange for resiliently urging the ring upwardly, and a plate fixed to the underside of the top jacket and means for lowering the top steam jacket for pressing the ring downwardly toward the flange whereby said plate will press against the upper surface of the brim on said top wall, and means for limiting upward movement of said ring relative to said flange, a lever pivoted to said stand and means to press the hat block placed within the crown of the hat on said pressing member downwardly against said crown, and means for circulating steam through the upper steam jacket, lower steam jacket and steam pot.

5. A hat blocking machine comprising a stand, rails attached to the stand, and extending therefrom, a spring supported upper steam jacket slidably mounted on the stand for up and down movement, a lower steam jacket slidably mounted on said rails and slidable from a position in front of the stand to a position over the stand and below the upper steam jacket, a steam pot fixed to the underside of the lower steam jacket, said lower steam jacket being formed with a central through opening communicating with the interior of the steam pot, a hat brim pressing member on the top of the lower steam jacket, said pressing member being provided with a top wall formed with a central opening so that the brim of the hat may be placed on said top wall with the crown of the hat projecting downwardly through the central opening in said top wall and through the central opening of the lower steam jacket and into the upper end of the steam pot, said presser member being further formed with a skirted wall extending downwardly from the outer end of said top wall and with an outwardly extending flange at the lower end of said skirted wall and a ring slidably mounted and surrounding said skirted wall, spring means interposed between the ring and said flange for resiliently urging the ring upwardly, and a plate fixed to the underside of the top jacket and means for lowering the top steam jacket for pressing the ring downwardly toward the flange whereby said plate will press against the upper surface of the brim on said top wall, said top wall being formed adjacent its periphery with a groove adapted to receive a thickened edge at the periphery of the brim of the hat.

6. In a steam blocking machine, a steam jacket formed with a central through opening, a steam pot attached to the underside of the steam jacket, the upper end of the pot connecting with the opening in the steam jacket, a presser plate mounted on the steam jacket and having a top wall spaced above the steam jacket and formed with a central opening registering with the opening in the steam jacket, said presser plate having a skirted wall extending downwardly from the

top wall and being further formed with a flange extending outwardly from the lower end of said skirted wall, said top wall being formed with a groove at its periphery, a ring surrounding said skirted wall and being slidably mounted thereon for movement in the direction of the axis of said presser member, spring means for normally urging the ring upwardly, a top steam jacket above the bottom steam jacket, a plate fixed to the

10 underside of the top steam jacket, and means for moving the top steam jacket downwardly whereby said plate will depress the spring pressed ring and move toward the top wall of the presser member.

7. In a steam blocking machine a steam jacket formed with a central through opening, a steam pot attached to the underside of the steam jacket, the upper end of the pot connecting with the opening in the steam jacket, a presser plate mounted on the steam jacket and having a top wall spaced above the steam jacket and formed with a central opening registering with the opening in the steam jacket, said presser plate having a skirted wall extending downwardly from the top wall and being further formed with a flange

20 extending outwardly from the lower end of said skirted wall, said top wall being formed with a groove at its periphery, a ring surrounding said skirted wall and being slidably mounted thereon for movement in the direction of the axis of said presser member, spring means for normally urging the ring upwardly, a top steam jacket above the bottom steam jacket, a plate fixed to the underside of the top steam jacket, and means for moving the top steam jacket downwardly whereby

30 said plate will depress the spring pressed ring and move toward the top wall of the presser member, and means for supplying steam to the bottom steam jacket, top steam jacket and steam pot.

40 8. In a hat blocking machine a presser member having a top wall formed with a central opening adapted to receive the crown of a hat with the brim of the hat contacting said top wall, said presser member having a skirted wall extending downwardly from the top wall and being further formed with a flange extending outwardly from the lower end of said skirted wall, a ring surrounding the skirted wall and being slidably mounted thereon, compression springs interposed

45 between the ring and said flange, said top wall being formed at its periphery with a groove all around to receive a thickened edge of the brim on said top wall.

9. In a hat blocking machine a steam jacket formed with a central opening, a steam pot attached to the underside of the steam jacket and communicating with the central opening in the steam jacket, a presser member fixed to the top of the steam jacket, said presser member having a top wall formed with an opening through which the crown of a hat may pass downwardly from the opening in the steam jacket and into said pot with the brim of the hat contacting the upper surface of the top wall, said presser member having an annular wall extending downwardly from the top wall, a ring surrounding said annular wall and being slidably mounted thereon, and spring means to raise the ring above the upper surface of the top wall, said spring means being interposed between the ring and said presser member.

10. In a hat blocking machine a steam jacket formed with a central opening, a steam pot attached to the underside of the steam jacket and communicating with the central opening in the

steam jacket, a presser member fixed to the top of the steam jacket, said presser member having a top wall formed with an opening through which the crown of a hat may pass downwardly from the opening in the steam jacket and into said pot with the brim of the hat contacting the upper surface of the top wall, said presser member having an annular wall extending downwardly from the top wall, a ring surrounding said annular wall and being slidably mounted thereon, said spring means interposed between said ring and said annular wall to raise the ring above the upper surface of the top wall, and a top steam jacket above the bottom steam jacket and means for resiliently pressing the top steam jacket downwardly to depress said ring and to clamp the brim of the hat against said top wall.

11. In a hat blocking machine a steam jacket formed with a central opening, a steam pot attached to the underside of the steam jacket and communicating with the central opening in the steam jacket, a presser member fixed to the top of the steam jacket, said presser member having a top wall formed with an opening through which the crown of a hat may pass downwardly from the opening in the steam jacket and into said pot with the brim of the hat contacting the upper surface of the top wall, said presser member having an annular wall extending downwardly from the top wall, a ring surrounding said annular wall and being slidably mounted thereon, and spring means interposed between said ring and flange to raise the ring above the upper surface of the top wall, and a top steam jacket above the bottom steam jacket and means for resiliently pressing the top steam jacket downwardly to depress said ring and to clamp the brim of the hat against said top wall, said top wall being formed with a groove at the junction of the upper surface of the top wall and the outer surface of the annular wall to receive a thickened edge at the periphery of the brim of the hat.

12. In a hat blocking machine an upstanding stand, horizontal rail means on the stand, a bottom steam jacket slidably mounted on said rail means and movable from a position over the stand to a position spaced forwardly of the stand, said steam jacket being formed with a central opening, a steam pot attached to the underside of the bottom steam jacket and communicating with the central opening therein, a presser member on the bottom steam jacket, a ring surrounding said presser member and slidably mounted thereon for up and down movement, compression spring means interposed between the ring and the bottom steam jacket, a top steam jacket mounted for sliding up and down movement on the stand, said top steam jacket having a central opening, a plate attached to the underside of the top steam jacket, said top steam jacket having an inlet and an outlet, said bottom steam jacket having an inlet and an outlet, and said steam pot having an inlet and an outlet, means for feeding live steam to the inlet of the steam pot, means for draining steam from the outlet of the steam pot, means for feeding steam to the inlet of the top steam jacket, means for passing steam through the outlet of the top steam jacket to the inlet of the bottom steam jacket, and means for draining steam from the outlet of the bottom steam jacket.

13. In a hat blocking machine a steam jacket formed with a central opening, a steam pot attached to the underside of the bottom steam

jacket and communicating with the central opening in the steam jacket, a presser member having a top wall formed with a central opening and spaced above the bottom steam jacket, an annular skirted wall extending from the outer end of the top wall and a flange extending downwardly from the lower end of the skirted wall, said top wall having a central opening whereby the brim of a hat may be placed on said top wall with the crown of the hat projecting through the central opening therein, through the central opening in the bottom steam jacket and into the upper end of the steam pot, an annular ring surrounding and slidably mounted on said skirted wall, said annular ring being formed in its upper end with a plurality of downwardly extending sockets and its lower end with a plurality of upwardly extending sockets aligned with the first mentioned sockets, said ring being formed with vertical through openings interconnecting the top and bottom sockets, pins attached to said flange and passing through the bottom sockets and through said other openings and into the top sockets, heads at the upper ends of said pins, and coil compression springs surrounding said pins and interposed between the flange and the ring and projecting into said bottom sockets.

14. In a hat blocking machine a steam jacket formed with a central opening, a steam pot attached to the underside of the bottom steam jacket and communicating with the central opening in the steam jacket, a presser member having a top wall formed with a central opening and spaced above the bottom steam jacket, an annular skirted wall extending from the outer end of the top wall and a flange extending downwardly from the lower end of the skirted wall, said top wall having a central opening whereby the brim of a hat may be placed on said top wall with the crown of the hat projecting through the central opening therein, through the central opening in the bottom steam jacket and into the upper end of the steam pot, an annular ring surrounding and slidably mounted on said skirted wall, said annular ring being formed in its upper end with a plurality of downwardly extending sockets and its lower end with a plurality of upwardly extending sockets aligned with the first mentioned sockets, said ring being formed with vertical through openings interconnecting the top and bottom sockets, pins attached to said flange and passing through the bottom sockets and through said other openings and into the top sockets, heads at the upper ends of said pins, and coil compression springs surrounding said pins and interposed between the flange and the ring and projecting into said bottom sockets, said top wall being formed with a peripheral groove at the junction of the upper surface of the top wall and the outer surface of said skirted wall.

15. In a hat blocking machine a steam jacket formed with a central opening, a steam pot attached to the underside of the bottom steam jacket and communicating with the central opening in the steam jacket, a presser member having a top wall formed with a central opening and spaced above the bottom steam jacket, an annular skirted wall extending from the outer end of the top wall and a flange extending downwardly from the lower end of the skirted wall, said top wall having a central opening whereby the brim of a hat may be placed on said top wall with the crown of the hat projecting through the central opening therein, through the central

13

opening in the bottom steam jacket and into the upper end of the steam pot, an annular ring surrounding and slidably mounted on said skirted wall, said annular ring being formed in its upper end with a plurality of downwardly extending sockets and its lower end with a plurality of upwardly extending sockets aligned with the first mentioned sockets, said ring being formed with vertical through openings interconnecting the top and bottom sockets, pins attached to said flange and passing through the bottom sockets and through said other openings and into the top sockets, heads at the upper ends of said pins, and coil compression springs surrounding said pins and interposed between the flange and the ring and projecting into said bottom sockets, said top wall being formed with a peripheral groove at the junction of the upper surface of the top wall and the outer surface of said skirted wall, a top steam jacket above the bottom steam jacket, a plate fixed to the underside of the top steam jacket, means for slidably moving the top steam jacket downwardly so that said plate will first depress the ring and then clamp the brim of the hat against the top wall of said presser member.

16. In a hat blocking machine a steam jacket formed with a central opening, a steam pot attached to the underside of the bottom steam jacket and communicating with the central opening in the steam jacket, a presser member having a top wall formed with a central opening and spaced above the bottom steam jacket, an annular skirted wall extending from the outer end of the top wall and a flange extending downwardly from the lower end of the skirted wall, said top wall having a central opening whereby the brim of a hat may be placed on said top wall with the crown of the hat projecting through the central opening therein, through the central opening in the bottom steam jacket and into the upper end of the steam pot, an annular ring surrounding and slidably mounted on said skirted wall, said annular ring being formed in its upper end with a plurality of downwardly extending sockets and its lower end with a plurality of upwardly extending sockets aligned with the first mentioned sockets, said ring being formed with vertical through openings interconnecting the top and bottom sockets, pins attached to said flange and passing through the bottom sockets and through said other openings and into the top sockets, heads at the upper ends of said pins, and coil compression springs surrounding said pins and interposed between the flange and the ring and projecting into said bottom sockets, said top wall being formed with a peripheral groove at the junction of the upper surface of the top wall and the outer surface of said skirted wall, a top steam jacket above the bottom steam jacket, a plate fixed to the underside of the top steam jacket, means for slidably moving the top steam jacket downwardly so that said plate will first depress the ring and then clamp the brim of the hat against the top wall of said presser member, a stand, means on the stand to support said top steam jacket for sliding movement, and rail means on the stand slidably

14

supporting said bottom steam jacket, steam pot, presser member and ring for movement in a direction at right angles to the direction of movement of the top steam jacket.

- 5 17. A hat blocking machine comprising in combination, an upright stand, a top steam jacket floatingly mounted on the upper portion of said stand for up and down movement relative thereto, said top steam jacket being formed with a central opening, horizontal rail means on said stand and below said top steam jacket, a bottom steam jacket formed with a central opening therein, and slidably mounted on said rail means and movable from a position directly beneath said top steam jacket to a position spaced forwardly of said stand, a presser member on the bottom steam jacket and formed with a central opening for inserting a hat therein with its crown extending downwardly into the central opening of the lower steam jacket and the brim contacting the upper surface of the presser member, a hat block above said top steam jacket, and pivotally mounted to said stand for downward movement through the central opening of the top steam jacket and into the crown of the hat, means for lowering the top steam jacket to press the hat brim when said bottom steam jacket is directly beneath said top steam jacket, and means for supplying steam to said top and bottom steam jackets and to said crown of the hat.
- 10 18. A hat blocking machine comprising in combination, an upright stand, a top steam jacket floatingly mounted on the upper portion of said stand for up and down movement relative thereto, said top steam jacket being formed with a central opening, horizontal rail means on said stand and below said top steam jacket, a bottom steam jacket formed with a central opening therein, and slidably mounted on said rail means and movable from a position directly beneath said top steam jacket to a position spaced forwardly of said stand, a presser member on the bottom steam jacket and formed with a central opening for inserting a hat therein with its crown extending downwardly into the central opening of the lower steam jacket and the brim contacting the upper surface of the presser member, a hat block above said top steam jacket, and pivotally mounted to said stand for downward movement through the central opening of the top steam jacket and into the crown of the hat, means for lowering the top steam jacket to press the hat brim when said bottom steam jacket is directly beneath said top steam jacket, and means for supplying steam to said top and bottom steam jackets and to said crown of the hat, and means surrounding said presser member to aid in lifting said top steam jacket.
